GLOVE WITH IMPROVED GUNN

Morris L. Slimovitz, Newbern, Tenn.

Application October 12, 1949, Serial No. 121,015

2 Claims. (CL. 2—163)

1

This invention comprises novel and useful improvements in a glove with an improved Gunn and more specifically pertains to a reversible type of glove wherein the gloves may be reversed upon the hands of the wearer in order to reverse the position and functioning of the palm and back portions thereof, having an improved Gunn or second and third finger construction.

The principal object of this invention is to provide an improved construction of reversible glove together with an improved Gunn or intermediate finger assembly therefor.

The very important object of the invention is to provide a reversible glove wherein the seams joining the various portions of the glove are formed and disposed in such a manner as to not interfere with the flexing of the glove in either of its reversible positions upon the hands of the wearer.

A still further important object of the invention is to provide a reversible glove wherein the palm and back sections thereof may conveniently be formed of different materials in order to adapt the surfaces of the gloves to different uses and conditions of wear.

Yet another important object of the invention is to provide a reversible glove wherein the palm and back sections may be coextensive thereby reducing the number of dies required to make the glove and rendering the assembly of the glove more convenient by the interchangeability of the palm and back sections thereof.

A still further object of the invention is to provide a reversible glove in conformity with the foregoing objects wherein Gunns having coextensive palm and rear sections may be effectively employed.

A still further object of the invention is to provide a glove of the Gunn type wherein the Gunn element may be secured by only two seams along the second and third fingers thereof.

Still another object of the invention is to provide a double Gunn construction for gloves in which the Gunns are seamed along their adjacent sides only to thereby reduce the number of seams in the fingers of the glove.

An additional object of the invention is to provide a reversible glove construction which is equally adapted for forming the intermediate fingers of a double Gunn or two single Gunns, and wherein the seams by which the Gunns are formed and are attached to the glove are positioned so as not to interfere with the flexing of the glove in either of its reversible positions of use.

2

And yet another object of the invention is to provide an improved construction of reversible glove of the Gunn type wherein the elements making up the glove may be assembled by employing a cylinder sewing machine with the known advantages of the rapid and efficient sewing of such a machine.

And a final important object of the invention to be specifically enumerated herein, is to provide an improved construction of reversible glove of the Gunn type in which all of the seams are disposed in such a manner as to impose a minimum of discomfort and opposition to flexing of the glove in either direction in accordance with the reversible use of the glove, and which may be formed of coextensive portions and sections, with a minimum number of seams and with a minimum of parts.

These, together with various ancillary features and objects of the invention which will later become apparent as the following description proceeds, are attained by the present invention, preferred embodiments of which have been illustrated by way of example only in the accompanying drawings, wherein:

Figure 1 is an elevational view of a reversible glove of the double Gunn type in accordance with the principle of this invention;

Figure 2 is an elevational view of the glove of Figure 1 during the course of its assembly, and showing the manner in which the double Gunn is applied to the palm and back sections to form the second and third fingers of the glove;

Figure 3 is a horizontal sectional view taken substantially upon the plane of the section line 3—3 of Figure 1 and showing the construction and seam arrangement of the fingers of a glove;

Figure 4 is a group diagrammatic view of the various elements employed in fabricating the embodiment of glove illustrated in Figure 1 in accordance with the principle of this invention;

Figure 5 is an elevational view of a second embodiment of Gunn type of reversible glove having two Gunns secured thereto to form the second and third fingers of the glove;

Figure 6 is an elevational view showing a step in the fabrication of the glove of Figure 5, and illustrating in particular the initiation of the step of applying a Gunn to the palm and back sections of the glove;

Figure 7 is a view similar to Figure 6 but illustrating a step in the attachment of both of the Gunns to the palm and back sections of the glove to form the second and third fingers of the same;

Figure 8 is a horizontal sectional view taken substantially upon the plane of the line 8-8 of Figure 5 and showing the seam construction of the two Gunns of the glove of Figure 5; and

Figure 9 is a group plan view showing the elements employed in fabricating the glove of Figure 5.

Referring now more specifically to the accompanying drawings, wherein like numerals designate similar parts throughout the various views, attention is directed first to the preferred embodiment of the invention. For convenience in illustration Figures 1-4 disclose the improved double Gunn construction applied to a glove wherein the body of the same has its palm and rear sections formed integrally. As shown in Figures 1 and 4, the glove body 10 includes portions 12 and 14 which are coextensive and of identical construction, being joined along a medial line indicated by the dotted line at 16, whereby these sections may be folded upon each other. Since the sections 12 and 14 are identical, either may serve as the palm section and the other as the back section of the glove, the designation of these sections as palm and back therefore being a reference to one of their reversible uses. Upon the medial line 16, the sections 12 and 14 are cut away as at 18 to provide a recess for receiving the customary thumb 20, the latter being of any conventional known design and forming no part of the improvement of this invention.

The coextensive sections 12 and 14 are provided with outside finger portions 22, 24 and 26, 28, the portions 22 and 24 being coextensive and the portions 26 and 28 being likewise co-extensive, the portions 22 and 24 and the portions 26 and 28 being disposed symmetrically with respect to the medial line 16 so that when the sections 12 and 14 are folded together, portions 22 and 26 will form the front or the rear sections of the outside fingers, while the portions 24 and 28 will form their complementary front or rear sections to form the outside fingers of the glove.

In each of the sections 12 and 14, the finger portions of the outside fingers are spaced from each other to define an edge 30 and 32, this edge being employed to receive and attach the double Gunn employed with this embodiment.

The latter comprises a unitary sheet of material 34 which is foldable upon a medial line 36 and also upon a perpendicular line or axis 38 which is perpendicular to and intersects the axis or line 36 intermediate the ends of the same, as will be clearly apparent from Figure 4.

By these intersecting lines or axes, the Gunn portion 34 is divided into four areas as indicated at 40, 42, 44 and 46. The portions 40 and 44 are coextensive with each other and disposed in edgewise juxtaposed position to provide front and rear sections of a second or third finger, while the portions 42 and 46 are similarly disposed to form the other of the second and third fingers of the glove. In addition, the portions 40 and 42 are laterally juxtaposed upon the line or axis 36 to form the front or the rear sections of the second and third fingers, while the portions 44 and 46 are likewise laterally juxtaposed to form the other of the front or rear sections of the second and third fingers.

It will now be seen that the Gunn 34 is symmetrical with regard to both of the perpendicular axes 36 and 38, and that the front and

back sections of each of the second and third fingers are coextensive.

The Gunn 34 is provided with a transverse slot having a pair of slightly arcuate edges or rims 48 and 50, the axis of this slot lying upon the line or axis 38 previously mentioned, and the slot being symmetrically disposed with respect to the axis 36.

In assembling this embodiment of glove, the sections 12 and 14 are folded upon each other along the axis or line 16, so that the edges of the sections 12 and 14 will be co-terminus. The double Gunn section 34 is then folded upon the axis 38, so that the portions 40 and 42 will be coextensive with and respectively co-terminus with the portions 44 and 46, with the edge 48 being co-terminus with the edge 50. The double Gunn 34 is then placed upon the folded body portion 10 so that the edges 48, 50 are juxtaposed upon and coincide with the edges 30 and 32. Conveniently, the Gunn may be sewed to the body portion upon a well known type of sewing machine such as a cylinder sewing machine, the edge 48 being sewed to the edge 30, with the end F placed in registry with the end of the edge 30 as at D², and the edge 48 is then sewed to the edge 30 until the midportion E thereof is secured to the midportion G' of the section 12 whereupon the sewing is continued until the point D is secured to the point F².

The sewing further continues by which the edges 50 and 32 are joined together, so that the point G is secured to the point E' and finally the point F of the edge 50 is secured to the edge 32 at D².

Upon the completion of this step in the manufacture of the glove the double Gunn will now be secured to the body portion in the manner indicated in Figure 2.

Next, the juxtaposed outside edges of the portions 40 and 44 are secured together and similarly the outside edges of the portions 42 and 46 are sewed together whereupon the complete second and third fingers are formed. Thereafter, a seam is made to join the unattached edges of the sections 12 and 14 as well as those of the outer finger portions 22 and 24, and the outer edges of the outer finger portions 26 and 28. At this time the glove is now complete except for the addition of the thumb 20 which is effected in the usual manner.

It should be here clearly noted that by reason of the coextensive contours and shapes of the parts as described above, all of the various seams will be positioned equi-distant between the palm and back sides of the gloves, as clearly shown in Figure 3. From Figure 3 it will now be apparent that the seam indicated at 52 represents the seam by which the material 20 forming the thumb is joined, while the seam 54 represents the seam by which the portions 26 and 28 are secured to each other, the seams 56 and 58 constitute the means by which the front and back sections of the double Gunn are secured to each other to form the second and third fingers, while seams 60 and 62 respectively represent the seam upon the inner side of the fourth finger of the glove and the seam joining the juxtaposed outer edges of the sections 12 and 14 and of the portions 22 and 24.

It will further be apparent that each of the seams is disposed half-way between the front and rear surfaces of the glove so that they will impart the minimum resistance to bending of

the glove in either direction, thereby permitting the reversible use of the glove in either front or back position with the maximum facility.

It is particularly to be noted that in the double Gunn construction disclosed, a single unitary sheet of material is employed to provide the two intermediate fingers of the glove, and these two intermediate fingers are provided with only a single seam apiece, these seams being adjacent each other as shown in Figure 3. Obviously, the reduction of the customary number of seams in forming the intermediate fingers of the glove, greatly contributes to the flexibility of bending of the glove in either direction, and thus enhances the reversible operation of the glove.

In addition, it is to be noted that the insurance of the seams being located intermediate or medially of the front and rear sections of the glove is effected by the coextensive shape of the different sections and portions to be joined. This coextensiveness of the sections and portions thereof not only insures the desired location of the seams, and thereby contributes to the reversibility of the glove, but greatly simplifies the fabrication of the glove by unskilled laborers, reduces the number of sewing operations and enables the manufacture or sewing of the glove upon the well known and very economical cylinder type of sewing machine.

While the embodiment just described has been illustrated as having the body 10 formed of a unitary sheet of material, it is evident that the principles of the invention likewise embrace the forming of the body of two separate sections, but divided along the line 16, these sections being coextensive. Obviously, this use of separate but coextensive palm and back sections enables the use of different materials for these sections, whereby in one position of operation the material and wear surface of the glove will be particularly selected for a particular use or type of employment, while the other surface in the reverse position will be adapted for a different use. For example, a soft leather surface may be employed for one of the sections 12 and 14 when the glove is to be worn by truck drivers, while a much heavier grade of leather or other material may be employed for the other of sections 12 and 14 when the glove is being utilized by other workers such as loaders or the like. Moreover, the use of separate but coextensive sections 12 and 14 enables the realization of different decorative effects from identical sections.

With the construction and arrangement so far described, a double Gunn has been employed. While the primary objects and advantages of this invention are realized by the double Gunn construction, certain features and principles of the invention may likewise be attained by the use of separate Gunns for the second and third fingers. Such an arrangement is illustrated in the embodiment of Figures 5-9, in which for simplicity of illustrating the principles of the invention there is disclosed a reversible glove having separate palm and back sections. In this embodiment, the reversible glove includes the elements shown in plan in Figure 9, and comprises a body portion 10, a thumb 72 and a pair of Gunns 74 and 76.

The body 10 includes a pair of coextensive sections 78 and 80, one of which will constitute a palm and the other a back section of the glove, these sections having identical cut out portions 82 and 84 to receive the portions of material 86 and 88 from which the thumb 72 is formed. As

in the preceding embodiment, the sections 78 and 80 are provided with integral extending portions 90, 92 and 94, 96, respectively, the two former portions forming either the front or rear surface of the outside fingers of the glove, while the two latter portions form the other surface of the outside finger portions. Between the portions 90 and 92, the section 78 is provided with an edge 98, a similar edge 100 being disposed between the portions 94 and 96.

In accordance with the customary practice, the Gunns 74 and 76 are appropriately shaped in accordance with the conventional practice, being provided with wedge-shaped notches 102 and 104. The Gunns 74 and 76 are adapted to be folded at their intermediate portion so that the mid-portions of the same may be sewed respectively to the edges 98 and 100 whereby each Gunn will constitute a front or a back portion of the second and third fingers.

In assembling this form of the invention, one of the Gunns 74 is disposed as shown in Figure 6 with an edge 98 of the slot 102 placed upon the edge A' or substantially at the end of the edge 98, and one edge of the slot 102 is then sewed to the edge 98 so that the end of the slot 102 as at B is secured to the middle of the edge 98 as at B', and upon continuing the sewing, the other edge of the slot and the remainder of the edge 98 are secured together so that the point C of the Gunn is secured as at C' to the edge of the section. The Gunn is now attached in the position shown in Figure 7 with the opposite open edges of the slot 102 being secured to the opposite ends of the edge 98, with the mid-portion of the slot being sewed to the mid-portion of the edge 98. Similarly, the other Gunn 76 is secured to the other edge 100 of the other section 80, whereby each Gunn constitutes the front or a rear section for the two middle fingers.

The adjacent edges of the Gunn 74 and 76 are then sewed together in the customary manner to form the seams 106, 108, 110, and 112, thus completing the middle fingers. The outer finger portions 92, 94 and 90, 96 are then joined upon their inner edges as by seams 114, 116 and their outer edges together with the outer edges of the glove sections 78 and 80 are then joined by seams 118, 120. The seam 122 secures the thumb portion to the glove body and the glove is now complete.

It should be noted that the two Gunn assembly of Figures 5-9 could likewise be readily employed when the two sections 78 and 80 are formed as an integral sheet element in the manner disclosed for the sections 12 and 14 of the embodiment of Figures 1-4.

From the foregoing, it is thought that the invention including its fabrication and operation will be readily apparent and further explanation is believed to be unnecessary.

However, since numerous modifications and changes will readily occur to those skilled in the art after a consideration of the foregoing specification and accompanying drawings, it is not desired to limit this invention to the exact construction shown and described, but all suitable modifications and equivalents may be resorted to, falling within the scope of the appended claims.

Having described the invention, what is claimed as new is:

1. In a reversible glove having palm and back portions each having two integral outside finger portions and an intermediate finger assembly secured to said palm and back portions between

said two outside finger portions; said intermediate finger assembly comprising a unitary elongated sheet of material having second and third finger portions disposed in longitudinal juxtaposition upon said sheet, each of said last-named portions having palm and back sections joining upon the longitudinal axis of the sheet, said sheet having a slot extending transverse to said longitudinal axis and terminating inwardly of the longitudinal edges of the sheet and disposed between said second and third finger portions, whereby the front and back sections may be folded upon said longitudinal axis and the second and third finger portions may be folded about an axis perpendicular to the slot and longitudinal axis and intermediate the ends of the slot and axis to position the unjoined edges of said sections between said second and third fingers portions.

2. A reversible glove including palm and back portions, two integral outside finger portions on said palm and back portions, an intermediate finger assembly forming second and third fingers secured to said palm and back portions between said outside finger portions, said intermediate finger assembly comprising a unitary elongated sheet of material having second and third finger portions disposed in longitudinal juxtaposition upon said sheet, each of said last-named portions having palm and back sections joining

5 10 15

upon the longitudinal axis of the sheet, said sheet having a slot extending transverse to said longitudinal axis and terminating inwardly of the longitudinal edges of the sheet and disposed between the said second and third finger portions, a seam securing the rim of said transverse slot to the palm and back portions whereby said slot provides entrance into the second and third fingers of the glove, a single seam joining the longitudinal edges of the sheet and securing the palm and back sections of the second and third finger portions together, said last-mentioned seam being disposed between the second and third fingers of the glove and equidistantly between the palm and back portions thereof.

MORRIS L. SLIMOVITZ.
